CLAIM

The ornamental design for a folding baby dining chair, as shown and described.

DESCRIPTION

FIG. 1 is a perspective view of a folding baby dining chair showing my new design;

FIG. 2 is a front view thereof;

FIG. 3 is a rear view thereof;

FIG. 4 is a left side view thereof, a right side view being a mirror image of the left side view; and,

FIG. 5 is a top view thereof, a bottom view being omitted since the bottom is invisible in use.
